L. A. PERRAULT, OF NATCHEZ, MISSISSIPPI.

Letters Patent No. 100,321, dated March 1, 1870.

IMPROVEMENT IN BOTTLE-COCKS.

The Schedule referred to in these Letters Patent and making part of the same.

To all whom it may concern:

Be it known that I, L. A. PERRAULT, of Natchez, in the county of Adams, and State of Mississippi, have invented a new and improved Bottle-Cock; and I do hereby declare that the following is a full, clear, and exact description thereof, which will enable others skilled in the art to make and use the same, reference being had to the accompanying drawings forming part of this specification.

This invention relates to improvements in cocks for bottles, jugs, and other like articles, and consists of a cock attached to the cork or other plug, and having a turning plug, provided with a loose key for operating it, the said cock having at the end of the tube projecting through the cork a pair of wing or friction-plates, so connected to it and bearing against the inner walls of the bottle that a sliding tube or a piece of steel or other wire within the cock-tube, and acted on by the cock-plug when turned to stop the passage of the liquid, will force the wing-plates against the walls of the bottle, so as to prevent the withdrawal of the cork.

Figure 1 is a sectional elevation of my improved bottle-cock, and

Figure 2 is another sectional elevation, taken at right angles to the section fig. 1.

Similar letters of reference indicate corresponding parts.

A is the cock-tube.

It extends through the cork B and receives through opposite openings in the sides, below the cork, the end C of the curved wing or friction-plates D, which bear against the inner walls of the neck of the bottle.

E is an inner tube, or it may be a rod of wire placed within the tube A, between the plug and the ends C of the friction-plates.

This tube is beveled at the upper end, so that the plug F, turning in the direction indicated by the arrow, will force the tube down on the ends C of the plates D, and force the latter against the side of the bottle, to hold the cork B against being drawn out at the same time that the passage for the contents of the bottle is closed by the plug F.

The latter is shaped at the place for the passage of the liquid in the elliptic form shown in cross-section in fig. 2, so that when turned against the beveled upper end of the wire in the direction represented by the arrow, it will not be obstructed thereby.

When the plug F is turned to allow the liquid to escape, the weight of the plates D will raise the tube, and the plates will be free to allow the withdrawal of the cork if desired.

The tube A is made in two parts, screwing together at the top of the cork, so that the part with the plug may be readily attached or detached, as required for use.

Having thus described my invention,

I claim as new, and desire to secure by Letters Patent—

The combination with the cock-tube A and plug F of the tube or rod E and clamping or friction-plates D, substantially as specified.

L. A. PERRAULT.
